[57] CLAIM

The ornamental design for an exhaust hood for a rotisserie oven, as shown and described.

DESCRIPTION

FIG. 1 is a front elevational view of the exhaust hood for a rotisserie oven, showing a typical embodiment of our new design;

FIG. 2 is a left-side elevational view;

FIG. 3 is a section taken at line 3—3 in FIG. 1 and viewed in the direction of the arrows;

FIG. 4 is a top plan view;

FIG. 5 is a bottom plan view; and,

FIG. 6 is a bottom perspective view.

The appearance of the rear is a mirror image of the appearance of the front.

The appearance of the right-hand side is a mirror image of the left-hand side.

The broken lines in FIGS. 1 and 2 are intended to show a rotisserie oven environment for the exhaust hood, but are not a part of the claimed design.
